UNITED STATES PATENT OFFICE.

MARSHALL B. OGDEN, OF FOND DU LAC, WISCONSIN.

IMPROVED DOOR-BELL.

Specification forming part of Letters Patent No. **43,924**, dated August 23, 1864.

To all whom it may concern:

Be it known that I, MARSHALL B. OGDEN, of Fond du Lac, in the county of Fond du Lac, in the State of Wisconsin, have invented a new and useful Improvement in Gong Door-Bells; and I do hereby declare that the following is a full and exact description thereof, reference being had to the accompanying drawings, and to the letters of reference marked thereon.

My invention consists in a peculiar construction and arrangement of gong door-bells.

In the accompanying drawings, Figure 1 represents a section through the gong, bed-plate, and door-casing, showing also the hammer and devices for operating the same. Fig. 2 is a detached view of the hammer, showing also the motion of the hinged tail of the hammer.

In Fig. 1, A represents a portion of the door-casing to which the bed-plate B is attached. A forked standard, C, is cast with the bed-plate, and serves for mounting the gong D, which may be fastened by a screw passing through the center of the gong and entering the standard C. (In the drawings, one part of this standard C is cut away.) A short arm, E, supports the hammer-lever F, and has a projecting stop, e, to limit the motion of the lever. The hammer-lever is curved like the neck of a swan, and it is tilted forward by means of a coiled spring, G. A hinged piece, H, projects beyond the coiled spring so as to meet and catch the hook M when the door-knob is pulled, as shown in red lines. Thus

the hammer is tilted, and the hinged piece H allows the hook M to return to its place without disturbing the hammer. When the hammer is thus tilted, the coiled spring G returns the hammer with a sudden stroke upon the gong D, and the coiled spring L returns the shank and knob to their places, as seen in black lines. The motion of the hinged piece H is shown in Fig. 2.

The door-knob and shank may be of the usual form, the shank being provided with the spring L and hook M.

In attaching the bell or gong the head of the hammer is turned upward, while the hinged piece H hangs downward, so that this piece will fall to its place after being moved backward by the hook M in passing, as described.

The plate B has a rim, b, extending round the whole circumference of the plate.

Having thus fully described my invention, what I claim, and desire to secure by Letters Patent of the United States, is—

1. The arrangement and combination of the hammer F with the hinged piece H, coiled springs G and L, and hook M, for striking the gong, substantially in the manner set forth.

2. The hinged piece H, for facilitating the tilting of the hammer and the return of the hook M, substantially in the manner and for the purposes set forth.

MARSHALL B. OGDEN.
